CLAIM

The ornamental design for a collar for a mixer, as shown and described.

DESCRIPTION

FIG. 1 is a top perspective view of the collar for a mixer, shown in environmental use, showing my new design;

FIG. 2 is a bottom perspective view thereof, shown in environmental use;

FIG. 3 is a front elevation view thereof, shown in environmental use;

FIG. 4 is a rear elevation view thereof;

FIG. 5 is a left side elevation view thereof, the right side being a mirror image;

FIG. 6 is a top plan view thereof;

FIG. 7, is a bottom plan view thereof;

FIG. 8, is a cross section view thereof, taken along line 8-8 in FIG. 7; and,

FIG. 9, is an exploded perspective view thereof.

The broken lines showing the hook in FIGS. 1-2 illustrate environmental structure and forms no part of the claimed design.

1 Claim, 5 Drawing Sheets
